[57] CLAIM

The ornamental design for a combined dispensing container, cap and applicator for a cosmetic product, as shown and described.

DESCRIPTION

FIG. 1 is a top and front perspective view of a combined dispensing container, cap and applicator for a cosmetic product showing my new design;

FIG. 2 is a front elevational view thereof, the undisclosed opposite side being a mirror image;

FIG. 3 is a bottom plan view thereof; and,

FIG. 4 is a top plan view thereof.
